(57)

CLAIM

The ornamental design for the cosmetic container, as shown and described.

DESCRIPTION

FIG. 1 is a perspective view of a cosmetic container of the present design;

FIG. 2 is a front elevational view of the cosmetic container of FIG. 1;

FIG. 3 is a right side elevational view of the cosmetic container of FIG. 1, the left side view being a mirror image thereof;

FIG. 4 is a top plan view of the cosmetic container of FIG. 1;

FIG. 5 is a bottom view of the cosmetic container of FIG. 1; and,

FIG. 6 is a rear elevational view of the cosmetic container of FIG. 1.
